UNITED STATES PATENT OFFICE

NEIL L. CAMPBELL, OF GLENDALE, OHIO, ASSIGNOR, BY MESNE ASSIGNMENTS, TO CARTHAGE MILLS INCORPORATED, OF CINCINNATI, OHIO, A CORPORATION OF OHIO

COMPOSITION FLOORING

Application filed June 29, 1926. Serial No. 119,454.

My invention relates to flexible base paint surfaced flooring, such as is formed by printing in differently colored paints upon a base such as asphalt saturated felt, or other 5 substance, which can be passed in a continuous piece through the required coating and printing operations.

The use of paint printed felt base material in the production of rugs, strips and 10 runners, printed in such a way as to simulate standard woven carpetings, has been very widely extended in recent years, in spite of the fact that the hard, glossy, wear 15 surface produced by the paint is not in any way similar to woven fabric, and is too cold and hard for domestic uses, except where oil cloth or linoleum had formerly been employed.

It is the object of my invention to embed 20 in the paint surface a fabric web material which itself is printed along with the base, and which is so open in its texture as to permit the majority of the wear surface to be printed as usual, through the spaces in 25 the fabric. Such a fabric, as for example, mosquito netting, when embedded in the ground coat, and printed over by the pattern coats of the printing process, will adequately meet the requirements of my in- 30 vention.

The ultimate product will show the fabric 35 in the form of ridges in the normal paint body, in such a way as to strikingly simulate a woven product throughout. The surface, of the new flooring is hard and long wearing, but there is none of the glossy surface appearance and feel, nor is the surface highly enough reflective to remain quite cold as does the usual paint surfaced floor- 40 ing.

The use of a fabric web of netting-like character with printing upon it, adds strength to the product against tearing. It holds the printed coatings from running, if 45 it is desired to loop the product in a dryer, immediately after printing. Its threads are quite definitely covered by paint, so as to be entirely waterproof, and since the design is printed over the top of them, the threads of 50 the fabric appear to be part of the whole

product instead of being merely embedded in the paint.

I accomplish my object by that certain construction and arrangement of parts to be hereinafter more specifically pointed out and 55 claimed.

In the drawings:—

Figure 1 is a perspective of a corner of a rug device made in accordance with my invention.

Figure 2 is a section showing in a considerably enlarged scale, the structure of the product.

In the preferred form of my product, I use a base of asphalt saturated felt. This 65 felt may be given a back coat of paint or colored wax to simulate a linoleum back, or may be left untreated, or coated and treated as is the wear surface.

In forming the product, the felt 1 is first 70 given a ground coat of paint as indicated at 2. This paint may be laid on fairly thick, and in a preferred process, will be quick drying in its nature, and susceptible of being printed upon while wet.

The netting 3 is applied from a roll and imposed by means of a roller to the ground coat 2, while same is wet or quite plastic. Or without use of a roller, the netting may be fed onto the paint surface as it is smooth 75 by a doctor in such a manner as to embed the fabric and cover its threads with the ground coat paint. The film of ground coat paint over the threads is indicated at 4.

The design is thus printed upon the 80 ground coat, in the particular instance where the paint has sufficient body to receive a printed surface, as soon as the fabric is applied, or if the ground coat is to be dried first, after this has taken place.

In any event, the design is printed as indicated by the film 5, over the coated threads of the netting and down through the openings thereof, upon the base paint, with the result of exposing the netting only in the 95 form of ridges in the finished surface.

The final product is dried as usual, in making floor covering, and cut into rugs or strips, etc., dependent upon the nature of the design imprinted thereon.

The product is quite different in appearance and function from a body which is impressed with a fabric, so as to form an intaglio design. The fabric leaves an embossed fabric-like surface over the whole product without in any way interfering with the design and its clearness.

The roughened surface is warm to the touch, under circumstances where a smooth unbroken paint surface is cold. The whole body is given greater tensile strength, and less expensive paints can be used, because of omission of costly ingredients used to give high gloss to the paint.

It is essential to my process that the fabric be of quite open work design, so that the design paints can be printed through it on the ground coat paint, since this not only avoids the problem of printing with paints on an expansive woven fabric substance, but it permits the fabric, prior to receiving the design, to be coated with the ground coat, and readily anchored by the paint, and submerged in a permanent resilient inert body from which it cannot be torn.

If desired, the netting can be passed through a bath of the ground coating paint, which is the same as forms the ground for the paint design, prior to being applied to the flooring body. Indeed, there is no insistence upon any particular processing to make my product.

Having thus described my invention what I claim as new and desire to secure by Letters Patent is:—

In a composition flooring, the combination with a base material of a paint surface thereon, including a ground coat, a piece of open-work fabric or netting embedded therein and coated thereby, and a design of paint imprinted upon the coated fabric threads and upon the ground coat, in the spaces between the threads.
